UNITED STATES PATENT OFFICE.

THOMAS G. SAXTON, OF LEXINGTON, KENTUCKY, ASSIGNOR OF ONE-HALF
TO CHARLES W. FOUSHÉE, JR., OF SAME PLACE.

AIR-EXCLUDER FOR FAUCETS IN BEER-COOLERS.

SPECIFICATION forming part of Letters Patent No. 355,218, dated December 28, 1886.

Application filed April 24, 1886. Serial No. 199,993. (No model.)

To all whom it may concern:

Be it known that I, THOMAS G. SAXTON, a citizen of the United States, residing at Lexington, in the county of Fayette, State of Kentucky, have invented certain new and useful Improvements in Air-Excluders for Beer-Coolers, &c., of which the following is a specification, reference being had therein to the accompanying drawings.

10 The object of my invention is to provide a device that will prevent air entering at the faucet-holes of beer-coolers and other similar receptacles containing liquors on tap. Said device consists, essentially, of a two-part ring 15 or annulus suitably hinged or otherwise jointed together, so as to be readily opened or separated, the central orifice thereof being adapted to surround the faucet, and an india-rubber or similar flexible gasket or packing being applied to said divided ring. This gasket is also 20 made in two parts, and when the device is fitted around a faucet and properly attached to the same an air-tight joint is formed without connecting to the cooler or chest, as hereinafter 25 more fully described.

In the annexed drawings, Figure 1 is a front elevation showing the two-part annulus in its open condition. Fig. 2 is a similar elevation, but showing the device clamped around a faucet, the latter being sectioned. Fig. 3 is a 30 horizontal section taken at the line $z-z$ of the preceding illustration. Figs. 4 and 5 show two different modifications of my invention.

$A A'$ represent two similar halves of a ring 35 or annulus, which is preferably made of thin metal, said halves being hinged or otherwise jointed together at B, in order that they may be readily opened or separated from each other when occasion requires. This joint is located 40 at one edge of the divided annulus, and near the opposite edge or side thereof a suitable retaining device is applied. In the present case this device is shown as consisting of a spring clasp or clip, C, hinged to the ring A' at D, 45 and having at its free end an eye, E, adapted to engage over a small pin or stump, F, projecting from the ring A.

G is a fixed tongue projecting from one of the rings, and arranged to slip in behind the 50 other ring when the device is closed.

H H' represent two similar halves of a flexi-

ble or yielding gasket or packing-ring, each ring being provided with an inner lip, I, and an outer lip, I'. These lips are adapted to engage over the inner and outer edges, respectively, of the divided annulus $A A'$, as more clearly seen in Fig. 3.

J represents a portion of a faucet passed through the customary hole, K, in a beer-cooler or other receptacle, L, for keeping liquor on tap.

The method of using this device is as follows: The faucet J is first passed through the hole K and inserted in the beer or other keg in the usual manner, after which act the sectional device is opened, as seen in Fig. 1, and then closed around said faucet, as represented in Fig. 2. When thus applied and the latch C engaged with the pin F, the device is securely mounted upon the faucet-barrel J, the inner lips, I I', fitting so snugly around the latter as to form an air-tight joint. Then by pressing the flat surfaces of the gasket H H' against the front of the cooler another air-tight joint will be formed. It will thus be seen that this simple and readily-applied device prevents air passing through the faucet-hole K, and thereby lowering the temperature of the cooler.

In the modification of my invention seen in Fig. 4 the device has a second but smaller opening, M, surrounded by a lip, N, said opening being designed to receive a tube that admits air into the keg for the purpose of venting the same. If desired, this opening may merge into the main or central orifice of the device. Again, in Fig. 3 the sides of the rings $A A'$ are convex or crowning, while in Fig. 5 the side of ring A is straight, thus indicating that the shape of the device may be varied.

It is preferred to make the gasket H H' of india-rubber, because the lips I I' can be cast therewith, thus enabling any bar-tender to apply a new gasket to the rings $A A'$ in case of an old gasket wearing out or being injured. After a keg has been emptied the device is detached from the faucet, the latter withdrawn, the keg removed, and a full one substituted for it. The faucet is then inserted in this keg and the device again applied, as previously described.

From this description it is evident my de-

vice is bodily detachable from the cooler or chest, and can be instantly applied without using a screw-driver or other implement. In this respect said device is radically different 5 from those air-excluders which are let into and screwed fast to the cooler, and require considerable time and labor to detach them.

I claim as my invention—

1. The combination, in a bodily detachable air-excluder for beer coolers, &c., of a two-part ring provided with a two-part gasket adapted to be fitted around a faucet and secured thereto without connecting to the cooler, for the purpose specified.
- 15 2. The combination, in a bodily detachable air-excluder for beer coolers, &c., of a two-part ring hinged together and provided with a retaining device, and a two-part gasket, which

latter is adapted to be fitted around a faucet without connecting to the cooler, for the purpose specified.

3. The combination, in a bodily-detachable air-excluder for beer-coolers, &c., of a two-part ring, A A', hinged together at B, and provided with a two-part gasket, H H', having inner 25 lips, I I, and outer lips, I' I', said ring A A' having a retaining device, but having no connection with the cooler, for the purpose specified.

In testimony whereof I affix my signature in 30 presence of two witnesses.

THOMAS G. SAXTON.
